UNITED STATES PATENT OFFICE.

ALONZO N. CALLAWAY, OF SAN ANTONIO, TEXAS.

PHOTOGRAPHIC-PRINTING FRAME.

SPECIFICATION forming part of Letters Patent No. 690,131, dated December 31, 1901.

Application filed September 21, 1901. Serial No. 76,056. (No model.)

To all whom it may concern:

Be it known that I, ALONZO N. CALLAWAY, a citizen of the United States, residing at San Antonio, in the county of Bexar and State of Texas, have invented a new and useful Photographic-Printing Frame, of which the following is a specification.

My invention relates to certain improvements in photographic-printing frames, and 10 has for its object to construct a frame of such character as to readily permit of the raising of the glass negative from its printing position for the inspection of the sensitized paper and to return the same accurately to printing position.

15 A further object is to insure the rigid holding of the glass negative without subjecting the same to any breaking strain.

A still further object is to provide a frame 20 of such construction as will permit of the spacing of the negative and the sensitized paper, so that when desired the rays of light may be diffused and the outlines of the picture toned and softened to produce an effect 25 similar to that of a porcelain print.

With these and other objects in view the invention consists in the novel construction and arrangement of parts hereinafter described, shown in the accompanying drawings, and particularly pointed out in the appended claims.

In the accompanying drawings, Figure 1 is a perspective view of a photographic-printing frame constructed and arranged in accordance with my invention. Fig. 2 is a longitudinal sectional elevation of the same, illustrating the sensitized paper and the glass negative arranged for compact printing. Fig. 3 is a view similar to Fig. 2, showing the sensitized paper moved to a short distance from the glass negative to permit diffusion of the light-rays. Fig. 4 is a transverse sectional elevation of the frame on the line 4-4, Fig. 2. Fig. 5 is a detail perspective view of the under side of the movable bed detached from the frame.

Similar characters of reference indicate corresponding parts throughout the various figures of the drawings.

1 designates a fixed frame formed of suitable side and end sections rigidly secured together in rectangular form and providing an open space for the reception of the movable bed 2. To one end of the frame is hinged a negative-carrier comprising oppositely-disposed side pieces 3, having grooves 4 and end pieces 5 and 6, the former being likewise slotted to receive the end of the glass negative 2, while the end bar 6 is cut away to a point below the grooves to permit of the ready 60 insertion or removal of the negative. In one or in both of the side grooves 4 are flat springs 7, adapted to bear against the edge or edges of the negative and exert sufficient friction to hold the negative securely in position.

At the center of the bar 5 is secured a thumb-plate 8 for the ready manipulation of the negative-carrier when it is desired to open or close the same during the printing 70 operation. At the extreme end of the carrier the side bars 3 are extended to form stops 9, adapted to abut against inclined shoulders 10, formed at the end of the main frame to prevent excessive opening movement. Between the frame and the negative-carrier small springs 11 are employed to assist in moving the carrier to the open position, said spring being preferably inserted in 75 sockets arranged in the end bar of the main frame and extending for a distance sufficient to impinge upon the plate-carrier.

The bed 2 is of such dimensions as to fit loosely within the open space formed by the bars of the main frame, and it is confined in 85 position by spring-pressed rods 12, carrying enlarged heads 13 for frictional engagement with the inner sides of the frame, the rods being pressed with sufficient force to hold the bed in position under stress of the springs 14, 90 which lock the negative-carrier in place, but permitting of the adjustment of the bed to a greater or less distance from the negative during the printing operation. The upper surface of the bed is covered, as usual, with felt 95 or similar material 15, forming a yielding back adapted to receive the sensitized paper 16, the paper being cut into proper size and of

sufficient length to extend beyond the ends of the bed and be there locked in position by the pivoted locking-loops 17. On the under side of the main frame are secured longitudinal bars or strips 20, which project inwardly from the sides of the frame and form supports for compression-springs 21, adapted to sockets 22 in the bed 2, the springs acting to keep the bed in an elevated position, but excessive movement being prevented by stop-plates 24, secured to the upper sides of the main frame.

When the various parts are assembled, the negative-carrier is held against the strips 24 by suitable spring-fingers 14, secured to the sides of the main frame and having bearing-fulcrums 25, which tend to keep them more firmly seated in locking position. These fingers can be readily moved to engage with the upper surface of the plate-carrier and will insure good contact with the glass negative and the sensitized paper during contact.

To the under side of the bed-plate are secured bracing-strips 27, extending longitudinally of the bed and serving partly as guides for levers or arms 28, as shown more clearly in Fig. 5. The levers or arms in the present instance are adapted to transverse grooves or recesses 29 in the rear of the bed and provided midway of their length with outwardly-bent portions forming loops, which may be engaged by the hand to operate the levers. The upwardly-bent ends of the levers are adapted to engage with the under side of the strips 24, and the latter for this purpose may be provided with metallic protecting-strips 31 to receive the thrust of the levers when the latter are operated.

The levers 28 serve to move the bed away from the negative, the extent of movement being dependent upon the result to be attained. To gain a porcelain effect, printing proceeds in the usual manner, with the negative in close contact with the sensitized paper until the printing is nearly finished. The levers are then operated to move the bed and the paper a slight distance from the negative, the light-rays being then diffused and producing a softer and more pleasing effect than is possible by continuous-contact printing. The bed is held in any position to which it may be adjusted by the contact of the friction-rods 12 with the inner surface of the main frame.

Various changes in the form and proportions of the device may be made within the scope of the claims without departing from the spirit or sacrificing any of the advantages of the invention.

Having thus described my invention, what I claim is—

1. In a photographic-printing frame, a frame, a bed supported thereby and adapted for the reception of a sheet of sensitized paper, a negative-carrier comprising a frame grooved for the reception of the negative, hinges connecting the carrier to the main

frame, and springs for securing said carrier in position.

2. In a photographic-printing frame, the combination with a bed, of a frame adapted for the reception and support of said bed, a negative-carrier hinged to the main frame and adapted for the reception of a glass negative, a thumb-piece carried by the negative-carrier, and springs for securing the carrier to the frame.

3. In a photographic-printing frame, the combination with a frame, of a paper-receiving bed, a negative-carrier hinged to the main frame and adapted for the reception and support of the negative, springs for securing the carrier to the frame, and separating-springs provided between the main frame and the negative-carrier, substantially as specified.

4. In a photographic-printing frame, the combination with a frame, of a paper-receiving bed, a negative-carrier hinged to said frame, spring-fingers secured to the main frame and adapted to be moved into position to secure the negative-carrier to the frame, and auxiliary fulcrums for said springs, substantially as specified.

5. In a photographic-printing frame, the combination with a negative-carrier, of an open frame, a movable paper-receiving bed guided therein, and operating-levers carried by said bed and adapted for engagement with a portion of the fixed frame, to adjust the relative positions of the bed and the negative.

6. In a photographic-printing frame, the combination with a negative-carrier, of a frame, a paper-carrying bed guided in said frame, friction-rods arranged between the sides of the bed and frame, and means for adjusting the relative positions of the bed and the negative, substantially as specified.

7. In a photographic-printing frame, the combination with a negative-carrier, of a frame, a paper-carrying bed guided thereby, and operating-levers fulcrumed on said bed and having laterally-bent end portions adapted for engagement with the fixed portion of the frame, substantially as specified.

8. In a photographic-printing frame, the combination with a negative-carrier, of a frame, a paper-receiving bed guided by said frame, springs disposed between the bed and frame and adapted to force said bed toward the negative, supporting-strips arranged on the rear of the bed, levers carried by the bed and having central looped portions forming engaging handles and laterally-bent end portions for operative contact with the frame, substantially as specified.

9. In a photographic-printing frame, the combination with a negative-carrier, of a frame having upper strips for contact with the frame forming the negative-carrier, a metal facing arranged on the under side of said strips, paper-receiving bed guided by the frame, levers carried by said bed and having engaging portions for operative contact with

the said metal facings, spring-pressed friction-
rods arranged on the bed for contact with the
inner face of the frame, and compression-
springs arranged between the frame and bed
; and adapted to force said bed toward the neg-
ative, substantially as specified.

In testimony that I claim the foregoing as

my own I have hereto affixed my signature in
the presence of two witnesses.

ALONZO N. CALLAWAY.
